CLAUDE C. HOCKLEY, OF PORTLAND, OREGON

METHOD AND APPARATUS FOR MAKING PAPER

Refile of application Serial No. 717,945, filed June 5, 1924. This application filed June 26, 1928. Serial No. 288,367.

My invention relates to the drying of the pulp or paper web while passing over a dryer section of a paper making machine, and has for its purpose the effecting of the rapid drying of the web, in its passage over said dryer section thereby to increase the daily production, and reduce the cost of manufacturing the paper.

My present application is to complete and 10 more particularly describe the method and apparatus described in my application for Letters Patent, filed June 5, 1924, Serial No. 717,945, entitled Process of making paper.

In making paper, as well-known, it is customary to form the web of the sheet on what 15 is generally called the "wet end" of the paper machine, and then remove the water, and finally drying the sheet by passing it over one or more steam-heated drying rolls.

As the sheet of paper comes to the dryer-rolls it has a relatively high moisture content 20 and therefore an efficient method and apparatus for drying the sheet is essential.

In the ordinary method of drying, the moisture in the sheet is driven out by the heat of 25 the hot dryer-rolls, and is carried off by a natural draft, or chimney, which leads from the hood which covers the dryer rolls.

In this mode of procedure the drying of 30 the paper web was to some extent hastened by passing over the dryer-roll a volume of moving, heated air, thereby to absorb and carry off the vapors emitted by the web; but it was thought that ample volume of air was 35 sufficient, and no attention was given to its velocity, nor the angle at which the sheet of air impinged upon the web of paper.

Furthermore economy in use of heat and power must be taken into consideration; and 40 to accomplish efficient drying with saving of heat and power is the object of my invention.

In brief I have discovered that the drying of the web of paper passing over a drying roll may be greatly promoted by impinging 45 upon the web of paper carried by said roll, a relatively thin transverse sheet of air preferably heated moving at high velocity, in the direction of motion of said roll, with said sheet of air constrained to a plane, which if 50 produced, would cut the circumferential

surface of said roll; and then causing the flow of said air to continue over a substantial longitudinal peripheral section of said roll and finally releasing said air.

My experiments have demonstrated that it 55 will not answer to direct the sheet of air in a plane which would be tangent to that section of the circumference of the drying roll impinged, thus substantially parallel with a plane touched by said section of the web at 60 the instant of impact thereon of the sheet of air. But instead, in order to promote the rapid drying of the web of paper, it is essential that the sheet of air be constrained to 65 strike the web in a plane which if produced, would cut the circle described by the web flexed about the drier roll. Such arrangement causes the sheet of air to impinge upon the web of paper in such manner as to break up 70 the film of moisture immediately overlying the web, which film if not broken up would tend to insulate the web from the drying air and reduce the effectiveness of the latter. This will slow up materially the drying effect 75 of said current of air; on the other hand by breaking up said insulating film of moisture the drying effect of said current of air is greatly promoted.

In order to carry my invention into practice, I found it convenient to use in combination with a drier roll, means for promoting 80 the drying of the web passed over the roll, comprising a hood open at one end and arranged to inclose and form a low passage-way over a circumferential section of substantial length of the drier roll, and means for blowing a sheet of air into the other end 85 of said hood at high velocity in the direction of the rotation of said roll, and in a plane which if produced would cut the circumferential surface of said drier roll.

Referring now to the accompanying drawings, illustrating my invention and forming part of this specification:

Fig. 1 shows a diagrammatic end elevation 95 of a dryer-roll of a paper making machine embodying my invention;

Fig. 2 shows a side elevation of the same;

Fig. 3 shows a longitudinal sectional detail of the pressure box and hood covering a cir- 100

5 circumferential segment of the dryer-roll and by which air is impinged at high velocity on the dryer-roll and further illustrates means for adjusting the orifices of the air-
5 ejecting nozzles discharging from the pressure box;

10 Fig. 4 shows a section taken on the line 4—4 of Fig. 3, and illustrates the manner in which the movable members of said air nozzles are adjustably carried on a pipe or shaft, which is journaled in the ends of the housing of the pressure box; and

15 Fig. 5 illustrates other means for adjusting the said air-ejecting orifices.

20 In the drawings, a^1 designates the outer casing, or hood; a^2 indicates the main shaft which is suitably mounted, and which carries the dryer roll a^4 , and a^3 is the exhaust by which the air current is removed after it 25 has passed under the hood and taken up the moisture, from the section of the paper sheet a^5 carried by the dryer roll. The arrows in Fig. 1 indicate the direction of travel of the sheet being dried; the entry point of the sheet in the drying apparatus being at a^6 and the exit point at a^7 respectively.

30 As shown in Fig. 1, two segments of the dryer roll are provided with my drying means—one on the right the other on the left—the parts of which means are designated by the same reference characters.

35 b^1 is the inlet pipe leading from a source of air supply under pressure, and preferably preheated in any convenient way; and b^2 is what is known as the pressure box. From this pressure box the air is projected tangentially against the wet paper sheet by the nozzles b^3 under the hood a^1 as shown in Fig. 3. Each nozzle b^3 is constructed to permit the 40 adjustment of its air projecting orifice; and I prefer to employ a single nozzle extended across the entire face of the dryer roll. Instead of such single nozzle a suitable closely arranged series of separate nozzles may be 45 provided, but I have not found such an arrangement to work out as well in practical results as by the employment of a single slit type of nozzle. I prefer to use two such long narrow nozzle orifices in the pressure 50 box, one above the other as illustrated in Fig. 3.

55 The hood a^1 is so arranged with respect to the underlying circumferential segment of the dryer roll as to provide a low passageway thereover, in order that only a relatively thin stratum of air at high velocity will be moved over the paper web under the hood and further will be held in close contact with the circumference of the dryer roll. 60 The high velocity of the air thus driven through the hood a^1 functions to break up the film of moisture-saturated air that otherwise would tend to form a shield over the paper web and reduce materially the speed 65 of its drying.

The air projected by the nozzles is preferably preheated, and blower (not shown) is used to drive the air through the pressure box at high velocity. And the air nozzles b^3 must be so arranged as to impinge upon the sheet of air upon the web carried by the drier roll, in a plane which if produced would cut the circumferential surface of the dryer roll since such accelerates the absorption and effects the rapid removal of the vapors carried and emitted by the web of paper.

70 The nozzles b^3 are preferably so arranged as to provide a narrow orifice or slit extending across the entire face of the dryer rolls, 80 as already mentioned. The construction is preferably such, also, that adjustment can be made of the orifice from the exterior of the pressure box. My preferred arrangement for this purpose is shown in Fig. 3 and 85 Fig. 4. The lower part of the nozzle consists of a metal plate c , set at a suitable angle and extending the width of the dryer roll as shown, and permanently secured in place. The upper companion nozzle plate d is, however, adapted to be moved with respect to the lower plate, to vary the opening between the two. As shown by Fig. 4 the upper nozzle plate d is carried by a series of spiders b^5 , mounted on a common shaft b^6 , journaled in 90 bearings located in the side walls of the pressure box b^2 , with one end of the shaft extending through the side wall; and on such projecting end of the shaft may be provided a wheel b^7 , or other suitable controlling means, 100 to facilitate the desired adjustment of the orifices of the nozzles. Set screws e permit the adjustment of said spiders b^5 on the shaft b^6 as desired.

105 In Fig. 5 a modified form of nozzle arrangement is shown. The upper plate of the nozzle b^3 is integral with the bottom of the pressure box, and the lower nozzle plate b^8 is adapted to be moved and adjusted with respect to the upper plate; the plate b^8 being carried on a movable supporting bracket secured in place by a bolt b^9 .

110 By the employment of my method and apparatus the moisture of the paper may be removed very rapidly, thus reducing the amount of steam used in drying, increasing the production; and, in consequence, reducing the cost of production. Furthermore, my method and apparatus removes the moisture so effectively as to make the work-room 115 more comfortable.

I claim:

120 1. In a paper making machine, the combination with a dryer roll of means for promoting the drying of the web of paper passed over said roll, comprising a hood open at one end and arranged to inclose and form a low passageway over a circumferential section of said roll and means including a nozzle for blowing a transverse sheet of air into the 125

other end of said hood at high velocity upon the web, in a plane which if produced would cut the circumferential surface of said dryer roll whereby to break up the film of insulating moisture enveloping the web of paper.

2. In a paper making machine, the combination with a dryer roll of means for promoting the drying of the web of paper passed over said roll, comprising a hood open at one end and arranged to enclose and form a low passageway over a circumferential section of said roll, and means including a pressure box provided with a series of nozzles adapted for blowing a transverse sheet of air into the other end of said hood at high velocity upon the web, in a plane which if produced would cut the circumferential surface of said dryer roll, whereby to break up the film of insulating moisture enveloping the web of paper.

3. In a paper making machine, the combination with a dryer roll of means for promoting the drying of the web of paper passed over said roll, comprising a hood open at one end and arranged to enclose and form a low passageway over a circumferential section of said roll, and means including an adjustable nozzle connected to a source of air under pressure for blowing a sheet of air into the other end of said hood at high velocity upon the web, in a plane which if produced would cut the circumferential surface of said dryer roll, whereby to break up the film of insulating moisture enveloping the web of paper.

35 4. In a paper making machine, the combination with a dryer roll of means for promoting the drying of the web of paper passed over said roll, comprising a hood open at one end and arranged to inclose and form a low passageway over a circumferential section of said roll, and means including a nozzle for blowing a transverse sheet of preheated air into the other end of said hood at high velocity upon the web in a plane which if produced would cut the circumferential surface of said dryer roll, whereby to break up the film of insulating moisture enveloping the web of paper.
